US00D571395S

(12) **United States Design Patent**
Katayama et al.

(10) **Patent No.:** **US D571,395 S**
(45) **Date of Patent:** **** Jun. 17, 2008**

(54) **PRINTER**

(75) Inventors: **Shigeharu Katayama**, Kakamigahara (JP); **Yasutake Yamaguchi**, Chiryu (JP); **Yousuke Mase**, Chita-gun (JP); **Shinji Kojima**, Nagoya (JP)

(73) Assignee: **Brother Industries, Ltd.**, Nagoya (JP)

(**) Term: **14 Years**

(21) Appl. No.: **29/225,708**

(22) Filed: **Mar. 21, 2005**

(30) **Foreign Application Priority Data**

Sep. 30, 2004 (JP) 2004-029831

(51) **LOC (8) Cl.** **18-02**

(52) **U.S. Cl.** **D18/56**

(58) **Field of Classification Search** D18/56, D18/55, 50, 4, 3, 12.3, 43, 44, 46-49, 14, D18/18, 21, 51, 54, 54.1, 58, 34.1, 34.9, 35, D18/35.1, 99; D9/435; D16/246-248, 237; D14/420-425, 462-470; 399/107; D11/217

(57) **CLAIM**

The ornamental design for a printer, as shown and described.

DESCRIPTION

FIG. 1 is a perspective view of a printer;

FIG. 2 is a top view thereof;

FIG. 3 is a cross-sectional view taken along the lines 3—3 of FIG. 2; and,

FIG. 4 is an enlarged view taken within the circle 4 of FIG. 3.

The broken lines are for illustrative purposes and form no part of the claimed design.
